UNITED STATES PATENT OFFICE.

ALBERT C. EVANS, OF BUTTE, MONTANA.

PRINTER'S LOCK-UP SQUARE.

Application filed December 12, 1923. Serial No. 680,214.

To all whom it may concern:

Be it known that I, ALBERT C. EVANS, a citizen of the United States, and a resident of Butte, in the county of Silverbow and

5 State of Montana, have invented certain new and useful Improvements in Printers' Lock-Up Squares, of which the following is a specification.

My invention relates generally to improvements in devices for locking up type forms, 10 and more particularly to a device which is adapted for use in conjunction with a printer's chase having no scale markings thereon, and it consists in the combination, constructions and arrangements herein described and 15 claimed.

The object of the present invention is to provide a device of the character described which affords facilities whereby it may be 20 used in conjunction with a printer's chase of the character described to indicate the position of a type form of any one of a plurality of sizes when the type form is in centered relation within the chase and to indicate at the same time the number of pieces 25 of furniture which will be required to secure the type form in centered position within the chase.

A further object of the invention is to 30 provide a device of the character described which is light in weight, economical to manufacture and conveniently and readily applicable to a printer's chase for the purpose set out in the foregoing.

35 Other objects and advantages will be apparent from the following description considered in conjunction with the accompanying drawings, in which:

Figure 1 is a plan view, showing an embodiment of the invention in position for 40 use on a printer's chase, the latter being shown diagrammatically; and,

Figure 2 is a side elevation of the chase with an embodiment of the invention thereon.

45 As is well known, considerable difficulty ordinarily is encountered and considerable time is consumed in ascertaining the centered position of a type form within a printer's chase having no scale markings thereon since 50 measuring operations are necessary to determine the centered position of the type form and to also determine the number of pieces of furniture which will be required to secure the type form within the chase. To 55 obviate the necessity of making any measurements in placing a type form of any one of

a plurality of sizes within a chase of the character described, I provide a device which I term a printer's square and which will be so referred to hereinafter.

60

As is well known, at the present time there are in use thousands of chases made of cast iron which are not susceptible of having pica markings placed upon them, and it is intended by the manufacture of this square, to 65 supply this need.

The printer's square comprises a right angular body, indicated generally at 1, and consisting of bar like members 2 and 3, respectively. The inner edges of the bar like 70 members 2 and 3 lie in planes extending at right angles to each other. The upper faces of the bar-like members 2 and 3 preferably are flat and lie in the same plane. The lower faces of the bar-like members 2 75 and 3 likewise are flat and lie in the same plane. The members 2 and 3 respectively are of such length that the inner edge of one of these members, in this instance the member 2, will coincide with length with the inner 80 edge of the transverse member of the printer's chase 4, and the inner edge of the member 3 will coincide in length with the inner edge of a longitudinal member of the chase 4 when the body 1 is placed upon the chase 4 with the member 2 disposed upon the aforementioned transverse member of the chase and the member 3 disposed upon the longitudinal member of the chase.

The member 3 is provided with a scale 85 extending on the upper face thereof along the inner edge of such member, the scale 3 including graduations spaced apart to indicate picas. The values of the graduations of the scale 3 increase in value from the outer 90 end of the member 3 and from a line extending transversely of the member 3 in the plane of the inner edge of the member 2 toward a line which extends transversely to the member 3 midway of the length of the inner edge 95 of the member 3, such transverse median line being indicated at 6.

In a like manner, the member 2 is provided with a scale indicated at 7, consisting of spaced apart graduations on the upper 100 face of the member 2 along the inner edge of the latter, the graduations of the scale 7 indicating picas, and increasing in value from the outer end of the member 2 and from a line extending transversely of the member 2 in the plane of the inner edge of the member 3 to a transverse line or grad-

uation 8 which extends transversely of the member 2 midway of the length of the inner edge of such member.

The member 3 also may be provided with a scale 9 extending along the outer edge thereof and consisting of graduations spaced apart to indicate units of linear measurement. The graduations of the scale 9 increase in value from the inner end of the member 3, that is the end thereof which lies in the plane of the outer edge of the member 2, toward the outer or free end of the member 3. The member 2 likewise may have a linear scale indicated at 10, provided thereon to extend along the outer edge thereof, the linear scale 10 having the graduations thereof marked to increase in value from the inner end of the member 2 that is from the end which lies in the plane of the outer edge of the member 3 toward the outer or free end of the member 2.

From the foregoing description of the various parts of the device, the operation thereof may be readily understood. The body 1 is placed upon the printer's chase so that the inner edge of the member 2 will substantially coincide with the inner edge of one of the ends or transverse members of the chase, and the inner edge of the member 3 will occupy a similar position in respect to the inner edge of one of the sides or longitudinal members of the chase. A type form of any one of a plurality of sizes may then be placed within the chase and will be in centered relation within the chase when the graduations of the scale 5 at the ends of the type form are of the same value and the graduations of the scale 7 at the sides of the type form are equal in value. This will be true since straight lines extending inwardly from the transverse median lines 6 and 8 will intersect each other at the center of the chase 4 when the body 1 has been positioned on the chase in the manner described. The values of

the graduations of the scale 5 at the ends of the type form and the values of the graduations of the scale 7 at the sides of the type form when the type form is centered within the chase will indicate the number of pieces of furniture which will be required to secure the type form within the chase in centered relation to the latter.

From the foregoing, it will be obvious that no measuring operation is required during the securing or locking up of a type form within a chase having no scale markings thereon when my printer's square is used in conjunction with the chase and a great economy in time and labor thus is effected. The printer's square 1 may be made of any suitable material, such as wood, brass or other light gage metal.

Obviously, the invention is susceptible of embodiment in forms other than that illustrated in the accompanying drawings, and I therefore consider as my own all such modifications and adaptations thereof as clearly fall within the scope of the appended claim.

I claim:

A device of the character described comprising a body consisting of two elongated flat members joined together at one end and extending at right angles to each other, each of said members having a printer's scale produced thereon and extending along the inner edge thereof, the printer's scale on each member terminating at one end in the plane of the inner edge of the other member and the scale on one of said members being equal in length to the inner edge of a transverse member of a printer's chase while the scale on the other member is equal in length to the inner edge of a longitudinal member of the chase, the graduations of each of said scales increasing in value from the ends of the scale to the median line thereof.

ALBERT C. EVANS.
